(57) **CLAIM**

The ornamental design for a suction cup hook, as shown and described.

DESCRIPTION

FIG. 1 is a front perspective view of a suction cup hook, showing my new design;

FIG. 2 is a rear perspective view thereof;

FIG. 3 is a front elevational view thereof;

FIG. 4 is a rear elevational view thereof;

FIG. 5 is a left side view thereof;

FIG. 6 is a right side view thereof;

FIG. 7 is a top plan view thereof;

FIG. 8 is a bottom plan view thereof;

FIG. 9 is a sectional view of 9-9 along the line in FIG. 3; and, FIG. 10 is a sectional view of 10-10 along the line in FIG. 5.

The dashed broken lines in the figures are for the purposes of illustrating portions of the suction cup hook, which form no part of the claimed design.

1 Claim, 9 Drawing Sheets(56)
